(57) **CLAIM**

The ornamental design for a outdoor window mounted candle holder, as shown and described.

DESCRIPTION

FIG. 1 is a front elevational view of an outdoor window mounted candle holder showing my new design;

FIG. 2 is a rear elevational view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a top and left side perspective view thereof; and,

FIG. 8 is a top and left side perspective view thereof, with the window frame, candle tube and electric bulb being shown in broken lines for illustrative purposes only and forming no part of the claimed design.
